United States Patent

Des. 236,765
Patented Sept. 9, 1975

236,765

SHIRRED TEXTILE FABRIC

Carl A. Wettering, Batesville, Ind., assignor to Batesville Casket Company, Inc.

Filed July 21, 1972, Ser. No. 273,979

Term of patent 14 years

Int. Cl. D5—05

U.S. Cl. D92—1 AB

The figure of the drawing is a top plan view of a shirred textile fabric showing my new design, the ridged rows being equally spaced across the width of the fabric.

I claim:

The ornamental design for a shirred textile fabric, as shown and described.
